UNITED STATES PATENT OFFICE.

JOSEPH NIXON, OF WAVERTREE, LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

AUTOMATIC SWITCH.

Application filed October 31, 1924, Serial No. 746,947, and in Great Britain November 1, 1923.

The present invention relates to improvements in or relating to automatic switches as used in telephone systems and more particularly to improvements in the bank contact construction in switches of the two directional type. Such switches usually have ten vertical steps and ten rotary steps, so as to have access to a total of 100 lines. In selector switches where hunting operations take place on the different levels, it is desirable to provide additional facilities for determining how often all the lines of a particular group are busy. For this purpose it has been proposed to provide an additional set of line and test contacts throughout the switches so as to provide for eleven lines instead of ten. This has the disadvantage that extra contacts are provided which are not required in switches of the final selector type unless two different types of switch banks are manufactured. It has also been proposed in British Patent No. 24343/14 to employ an auxiliary set of contacts adapted to be engaged by the test wiper for this purpose.

The object of the present invention is a constructional improvement to enable the desired results to be obtained with the minimum of expense in conjunction with a switch structure having access to ten sets of line contacts only in a level. This is attained according to the present invention by providing an additional contact only for each level of the bank corresponding to the test contacts. In a well known construction the contact banks are arranged in two parts, one vertically over the other; in one the line contacts are arranged on each side of an insulating sheet and adapted to be wiped over simultaneously by the rotating pair of line wipers. In the other the test contacts are single contacts separated by a much thicker insulation so that the distance between contacts corresponds to the step between different levels. A convenient way of carrying out the invention is therefore to substitute for the thick insulation two thin insulations and arrange a metal plate in the form of an arc corresponding in shape with the insulations separating the contacts but provided with a tooth slightly offset so as to be in alignment with the test contacts of the different rows, and placed in a position corresponding to an eleventh contact. This enables in a very convenient manner a meter to be operated every time all the lines in a group are busy and connection is established with the final contact of a row. The brass strip carrying the eleventh contact is conveniently provided with a soldering tag to which the meter may be directly connected. In order to give the subscriber the busy signal arrangements may be employed in conjunction with the arrangement above described such as described in the previously mentioned Patent No. 24343/1914.

An embodiment of the invention is shown by way of example, in the annexed drawing, in which

Fig. 1 is a plan view of the bank assembly.

Fig. 2 is a part elevation thereof looking in the direction of the arrow shown in Fig. 1, whilst

Fig. 3 is a cross-section on the line 3-3 of Fig. 1.

The bank comprises in the usual manner ten rows of contacts, 10 assembled together with interposed insulation by means of clamping plates 11 and bolts or the like 12. Each contact is extended at the rear to form a soldering-tag portion 13 in well known manner.

According to the invention the insulation between two rows of contacts is formed by two thin insulating strips 14, instead of the usual single thick strip, between which is placed a metal plate 15 in the form of an arc corresponding in shape with the insulating strip 14. The upper row of contacts 10 and the lower plate 15, i. e. those nearest the clamping plate 11, are insulated from the latter plates by insulating strips 16. Each plate 15 is provided at its end with an off-set portion as shown in Fig. 2, to form a contact 17 in line with the contacts 10 and in a position corresponding to an eleventh contact. A soldering contact 18 is advantageously also formed on each plate 15, in order that the meter, which is adapted to operate when the wiper moving over the bank engages the contact 17, i. e. when all the lines connected to the bank are busy, may be directly connected thereto.

The clamping plates 11 are provided with the usual holes 19 in order that the bank may be secured to the switch frame. The contacts 10 may be provided with thin insulating strips 20 in addition to the strips 14.

It will thus be appreciated that a very con-

venient means has been provided for adding to a switch an extra contact in alignment with the test contacts while utilizing the same tools without alteration for the manufacture of the other parts which make up the contact banks, at the same time it should be understood that considerable modifications may be made in the constructional details without departing from the spirit of the invention, 10 for instance by mounting the strips having a contact corresponding to the eleventh contact on a supporting post and suitably insulating the same.

Having now particularly described and 15 ascertained the nature of my said invention and in what manner the same is to be performed, I declare what I claim is:

1. In a contact bank, a plurality of individual contacts arranged in a row or level, 20 a metal plate parallel to said row and insulated therefrom, and an off-set projecting piece on said plate, in line with said row of contacts and at the end thereof.

2. In a contact bank, a plurality of rows or levels of individual contacts, a plurality of plates separating said rows of individual contacts and insulated therefrom, and an off-set projecting piece on each of the metal plates, each projecting piece in line with a different row of contacts and at the end thereof to form an eleventh contact. 25 30

3. A test wiper contact bank for switches of the type used in automatic or semi-automatic telephone systems, comprising a plurality of rows or levels of test contacts, an arcuate metal strip between two levels of said test contacts and insulated from said two levels by two thin insulating strips, and an off-set portion on said strip forming a contact in line with the test contacts of one of said levels and in a position corresponding to an auxiliary or eleventh position. 35 40

Signed by me at Liverpool, England, this 14th day of October, 1924.

JOSEPH NIXON.
